UNITED STATES PATENT OFFICE.

GEORGE H. F. HOLY, OF PITTSBURGH, PENNSYLVANIA, ASSIGNOR TO WESTINGHOUSE ELECTRIC & MANUFACTURING COMPANY, A CORPORATION OF PENNSYLVANIA.

LOCOMOTIVE.

1,384,466.

Specification of Letters Patent. Patented July 12, 1921.

Application filed May 26, 1917. Serial No. 171,149.

To all whom it may concern:

Be it known that I, GEORGE H. F. HOLY, a citizen of the United States, and a resident of Pittsburgh, in the county of Allegheny and State of Pennsylvania, have invented a new and useful Improvement in Locomotives, of which the following is a specification.

My invention relates to locomotives, and particularly to industrial locomotives for service in mines.

One object of my invention is to provide a locomotive having a single propelling unit which is directly connected to two driving axles in an improved manner to permit vertical rotative movement of the axles relative to each other, and to thus permit the locomotive to accommodate itself to various track irregularities.

More specifically, my invention embodies a locomotive of the above-indicated character which is provided with two axles having driving wheels mounted thereon, an auxiliary frame having a two-point support on one of said axles and a pivotal support on the other axle, and a motor mounted on said frame and having a driving connection with each of said axles.

In an industrial locomotive having two pairs of wheels, it is very desirable to apply power to each pair of wheels in order to increase the efficiency of the locomotive. Although in many cases a separate driving unit is connected to each axle, it is preferable to have a single driving unit connected to the two axles in order to reduce the cost of the locomotive.

Moreover, in a locomotive of the above-indicated character, it is very desirable to permit the various axles to effect vertical rotative movements relative to each other in order to insure good tracking characteristics of the locomotive. However, when a locomotive is provided with a single driving unit connected to two axles, special provision must be made to permit said relative movement between the two axles.

There have heretofore been two principal types of locomotives having but a single driving motor. In the one type, the single motor has been geared to one pair of driving wheels and side rods have been employed for connecting all of the pairs of driving

wheels. In the other type the motor has been geared to one axle and a flexible connection, as for example, a chain has been employed between the two axles. Although these two types of locomotives permit relative vertical movement of the two axles, they are objectionable because of the large number of moving parts that are necessary for interconnecting the two pairs of driving wheels and because of the danger to the men who operate them.

In a locomotive constructed in accordance with my invention a single motor is geared to and is mounted on the two axles in an improved manner to transmit the driving effort of the motor to the axles and to permit one of said axles to effect a vertical rotative movement relative to the other axle.

In the accompanying drawing, Figure 1 is a plan view of a locomotive constructed in accordance with my invention; Fig. 2 is a side elevational view of the locomotive illustrated in Fig. 1, and Fig. 3 is a plan view of an auxiliary frame that supports one end of the motor-supporting frame.

Referring to the accompanying drawing, a locomotive 1 is provided with two pairs of driving wheels 2 and 3 which are respectively mounted upon the axles 4 and 5. Side frames 6 having cross connections 7 therebetween are mounted on the axles 4 and 5 outside the driving wheels 2 and 3 in any convenient and approved manner. However, if desired, the relative positions of the side frames 6 and the driving wheels may be changed.

A motor supporting-frame 8 is mounted upon the axles 4 and 5 between the pairs of driving wheels 2 and 3 in a manner to permit the axle 5 to effect a movement of rotation relative to the axle 4 in a vertical plane. The frame 8 is provided with a two-point support on the axle 4 by means of bearings 9 and 10, the bearing caps for the bearings 9 and 10 being located below the axle 4 in order to prevent the caps from carrying the weight of the frame 8. Side members 8^a extend parallel to the side frames 6, and horizontally for a short distance and then curve upwardly to pass over the axle 5. An end member 8^b and an intermediate cross member 8^c are located on opposite sides of the axle 5 and parallel thereto, the end mem-

ber 8^b being provided with a bearing 15 and the cross member 8^c being provided with a bearing 21.

An auxiliary supporting frame 11, essentially rectangular in shape, has supporting bearings 12 and 13 on the axle 5. A bearing 14 and a short shaft 15^a are provided on the frame 11, located transversely to the bearings 12 and 13. The stub shaft 15^a is mounted in the bearing 15, thus bringing the bearing 14 adjacent to the cross member 8^c.

A motor 16, which is mounted upon the frame 8, is provided with a pinion 17 which meshes with a gear wheel 18 that is rigidly mounted upon a shaft 19. The shaft 19 is mounted in bearings 20 and 21 upon the frame 8 and is provided with beveled pinions 22 and 23 near its ends, the pinions meshing with beveled gears 24 and 25 that are rigidly mounted upon the axles 4 and 5. The bearing 21 which supports the shaft 19 on the frame 8 is provided with an extended bearing brass 26 upon which the bearing 14 of the auxiliary frame 11 is loosely mounted. The bearings 12 and 13 for supporting the auxiliary frame 11 on the axle 5, and the bearings 14 and 15, it may be noted, provide in effect a double pivotal connection for the frame 8 upon the axle 5. The part of frame 8 connected to and adjacent to the axle 4 may have a turning movement relative to axle 5, in a vertical plane parallel to the rails, by means of the bearings 12 and 13 mounted on the axle 5. The axle 5 and the auxiliary frame 11 may have a turning movement relative to the axle 4 and the frame 8, in a vertical plane at right angles to the rails, by means of the pivotal connection between the frame 8 and the auxiliary frame 11, provided by the bearings 15 and 14 and the shaft 15^a and the bearing brass 26. The caps for the bearings 14, 15, 20 and 21 are located underneath the locomotive in order to permit the dismantling of the bearings with facility.

From the above description, it is apparent that the axle 5 may effect a rotative movement relative to the axle 4 about a point aligned with the shaft 19 and in a vertical plane at right angles to the rails without interfering with the transmission of the driving effort of the motor through the beveled pinions and the beveled gear wheels to the two axles. Although the frame 8 is directly connected to the axles 4 and 5 by means of the shaft 19, the beveled pinions 22 and 23, and the beveled gears 24 and 25, it is apparent that the frame 8 is provided with the equivalent of a three-point support on the axles 4 and 5 and the axle 5 may effect a movement of rotation relative to the frame 8 in a vertical plane by reason of the beveled pinion 23 and the beveled gear 25 being joined at a point within the axis 65 about which the axle 5 will rotate.

Modifications in the structure and arrangement and location of parts may be made within the spirit and scope of my invention and such modifications are intended to be covered by the appended claims.

70

I claim as my invention:

1. In a locomotive, the combination with two axles having driving wheels mounted thereon, and a motor provided with means for transmitting the driving effort of the motor through the axles to the driving wheels, of means for supporting the motor at two different points on one of said axles and for so pivotally supporting the motor on the other of said axles as to permit both a bodily vertical movement and a pivotal movement of said axle in a transverse perpendicular plane.

75

2. In a locomotive, the combination with two axles having driving wheels mounted thereon, a motor, and means for transmitting the driving effort of the motor to the two driving wheels, of means for pivotally supporting the motor on one of said axles for vertical movement and for so pivotally supporting the motor on the second axle as to permit both a bodily vertical movement and a pivotal movement of said axle in a transverse vertical plane.

80

3. In a locomotive, the combination with two axles having side frames and driving wheels mounted thereon, a motor, and means comprising gear wheels for transmitting the driving effort of the motor to the two axles, of a supporting frame for said motor having a two-point support on one of said axles and a pivotal support on the other of said axles, so as to permit relative movement of the parts and constantly maintaining driving connection with said motor.

95

4. In an electric locomotive, the combination with two axles having driving wheels connected thereto and a propelling motor, of a plurality of gear wheels for connecting said motor to the two axles, and means for so pivotally supporting the motor on one of said axles as to constantly maintain driving connection therebetween.

105

5. In an electric locomotive, the combination with two axles having driving wheels mounted thereon and a propelling motor, of means comprising a plurality of gear wheels for connecting said motor to said axles, and means for pivotally supporting said motor and the connecting means attached thereto on one of said axles and for supporting the motor and the connecting means at two points on the other of said axles whereby said supporting means and one of said axles may have relative pivotal movement in intersecting vertical planes.

115

6. In a locomotive, the combination with two axles and driving wheels associated therewith, of a frame having a two-point pivotal support on one of said axles and a

120

130

5 pivotal support on the other axle whereby one of said axles may move bodily vertically and about said pivotal support in a single plane, a motor mounted on said frame and means for transmitting the driving effort of the motor to the driving wheels associated with the two axles.

7. In a locomotive, the combination with 10 two axles having driving wheels mounted thereon, side frames mounted on said axles outside the driving wheels, and a motor frame located inside of said driving wheels and pivotally supported on one of said axles, of a motor mounted on said motor frame, 15 an auxiliary frame pivotally mounted on said motor frame and supported by one axle and means mounted on the motor frame for transmitting the driving effort of the motor to the axles.

20 8. In a locomotive, the combination with two axles having driving wheels mounted thereon, and a propelling motor connected to each of said axles, of means for so pivotally supporting the motor on one of said 25 axles as to constantly maintain driving connection therebetween.

9. In a locomotive, the combination with 30 two axles, driving wheels mounted on said axles, a propelling motor, and means for transmitting the driving effort of the motor to the driving wheels, of means for so supporting the motor on both of said axles as to admit of a plurality of movements of one of said axles in a transverse perpendicular 35 plane.

10. In a locomotive, the combination with two axles having driving wheels mounted thereon, and a supporting frame disposed between said driving wheels, said frame 40 having a pivotal support on one of said axles and a two point pivotal support on the other of said axles, of a shaft mounted on said frame, gear wheels for connecting said shaft to the two axles, a motor mounted 45 on said frame, and gear wheels for connecting the motor to said shaft for transmitting the driving effort of the motors to both of said shafts.

11. The combination with two axles and 50 means for operatively connecting both of them for rotation together, operating means for said connecting means, of means for so supporting said first means at two different points on one of said axles and on the other 55 of said axles as to permit relative movement of the parts and constantly maintaining driving connection with said operating means.

12. In a locomotive, the combination with 60 two axles having driving wheels mounted thereon, a motor frame pivoted to one of said

axles, a motor carried thereby, means for transmitting the driving effort of the motor to two driving axles, means pivotally connected to one of said axles, and means permitting relative vertical and pivotal movements of said axles in vertical planes. 65

13. In a vehicle having a pair of rotatable axles, a motor frame pivotally mounted on one of said axles and mechanically 70 connected to said other axle, and a supporting frame pivotally mounted on said other axle and pivotally supporting said motor frame.

14. A locomotive provided with a motor 75 frame, a motor carried thereby for driving connection to two axles, one of said axles being mounted for both a bodily vertical movement and a pivotal movement in a 80 transverse perpendicular plane and constantly maintaining the driving connection with said motor.

15. In a locomotive, the combination of a plurality of axles, a motor frame supported therefrom, a motor mounted thereon, and 85 means for permitting one of said axles to move both vertically in a horizontal position and in a vertically transverse plane about a pivot and for constantly maintaining driving connection with said motor. 90

16. In a locomotive, the combination with two axles, a motor frame pivotally mounted on one of said axles, a motor mounted on said frame, an auxiliary frame having a two-point longitudinally pivotal support on 95 said motor frame and a two-point transverse support on the other of said axles, and means for operatively connecting both of said axles with said motor.

17. In a locomotive, the combination with 100 two axles, a motor frame pivotally mounted on one of said axles, a motor mounted on said frame, an auxiliary frame having a two-point longitudinally pivotal support on said motor frame and a two-point transverse support on the other of said axles, and 105 means for operatively connecting one of said axles with said motor.

18. In a locomotive, the combination with two axles, a motor frame pivotally mounted 110 on one of said axles, a motor mounted on said frame, an auxiliary frame having a two-point longitudinally pivotal support on said motor frame and a two-point transverse support on the other of said axles, and 115 means for constantly maintaining the operative connection between said axles and said motors.

In testimony whereof, I have hereunto subscribed my name this 18th day of May, 120 1917.

GEORGE H. F. HOLY.
